The ornamental design for a valve, as shown and described.

DESCRIPTION

FIG. 1 is a bottom view of a valve showing my new design; FIG. 2 is a top view thereof;

FIG. 3 is a right side view thereof;

FIG. 4 is a left side view thereof;

FIG. 5 is a front view thereof;

FIG. 6 is a rear view thereof;

FIG. 7 is a bottom rear perspective view thereof; and,

FIG. 8 is a top rear perspective view thereof.

The broken lines depict portions of the valve that form no part of the claimed design.
